**DEVICE HAVING A GLOW-DISCHARGE TUBE
AND GLOW-DISCHARGE TUBE INTENDED FOR
SUCH DEVICE**

Simon Mari Frouws and Jan Horseling, Eindhoven, Netherlands, assignors to North American Philips Company, Inc., New York, N.Y., a corporation of Delaware

Filed Nov. 14, 1960, Ser. No. 69,109

Claims priority, application Netherlands Dec. 8, 1959

4 Claims. (Cl. 315—269)

This invention relates to devices having a glow-discharge tube containing a cold non-activated cathode and an igniting anode near the cathode, the anode being substantially surrounded by a screen. It also relates to glow-discharge tubes intended for such devices.

Glow-discharge tubes are already known in which the anode screen is connected to the cathode through a high-ohmic resistor and wherein due to the small distance between the anode screen and the anode, which is no more than a few times the free length of the path of the electrons in the filling gas of the tube, only a very weak discharge sufficient for suppressing delays in ignition can occur between the anode and the said screen. Since the anode screen is connected to the cathode, such a tube is not suitable for alternating voltage between the main electrodes.

Tubes are also known in which the potential applied to the anode screen is not constant and wherein steps are taken for suppressing leakage currents to the anode screen, for example by preventing the occurrence of atomised layers on the insulator supporting the screen. Such tubes are suitable for alternating voltage between the main electrodes. In order to obtain sufficient voltage stability of the tube in the forward direction, the tube comprises an auxiliary anode which extends into the raised edge of an aperture of the cathode, which is remote from the anode. In this case, sufficient sensitivity in the pass direction can be obtained only if the igniting anode is at a negative potential.

However, in order to derive a negative potential for the igniting anode from the mains, it is necessary to interpose a transformer.

An object of the invention is to provide a device having a glow-discharge tube in which ordinary mains voltages with the voltage variations occurring therein can be used between the anode and the cathode, without objection, whilst nevertheless sufficient sensitivity to ignition by means of a positive igniting anode can be obtained.

According to the invention in a device having a glow-discharge tube containing a cold non-activated cathode and an igniting anode near the cathode and wherein the anode is substantially surrounded by a screen a second screen electrode is provided outside the anode screen and connected through a high-ohmic resistor to the cathode lead, whereas the anode screen is connected through a high-ohmic resistor to the anode lead, at least one of the two screens having a projection directed towards the other screen so that for the alternating operating voltage between the main electrodes a weak discharge occurs between the two screens at a distance from the main discharge path such that delays in ignition in the discharge path between the igniting anode and the cathode can be prevented, but decreases in igniting voltage in the main discharge path in one of the two directions do not occur.

Due to the high-ohmic resistors through which the screens are connected to the main electrodes and the guard discharge which occurs between the two screens, a voltage distribution between the anode, cathode and two screens is brought about in the tube to enhance the voltage stability thereof.

Preferably, in a tube intended for a device according to the invention, the anode screen is so arranged relative

2

to the anode that straight lines which do not intersect the screen can be drawn only between a portion of the surface of the cathode and the anode, whereas such lines cannot be drawn at all between the anode and that portion of the cathode to which the auxiliary discharge applies, or between the anode and the igniting anode, in this case, the auxiliary discharge between the two screens preferably takes place on that side of the anode screen which is remote as far as possible from the aperture for passing the main discharge.

In order that the invention may be readily carried into effect, it will now be described in detail, by way of example, with reference to the accompanying diagrammatic drawings, in which:

15 FIGURE 1 is an axial section of the bulb of a discharge tube with the electrodes viewed from the side;

FIGURE 2 is a plan view of the electrodes;

FIGURES 3 and 4 show two sections taken along the lines III—III and IV—IV of FIGURE 2, and

20 FIGURE 5 shows a simple circuit arrangement.

Referring now to FIGURES 1 to 4, a bulb 2 is sealed to a base 1 of the tube. A cathode 3 consists of a buckled molybdenum sheet which is secured to three supporting wires. An anode 4, which is made of nickel, is wire-shaped and surrounded by an anode screen 5. The cathode 3 has a sharply-pointed projection 6 and opposite thereto is an auxiliary anode 7 which is made of molybdenum strip. The anode screen 5 is surrounded by a buckled screen 8 which, like the anode screen 5, is made of nickel. The screen 8 carries a projection 9 which extends up to a distance of 0.5 mm. from the anode screen 5. The distance between the auxiliary anode 7 and the projection 6 of the cathode is 0.2 mm. The relative arrangement of the anode and the projection of the cathode can be clearly seen from FIG. 3. The relative arrangement of the cathode-screen projection 9 and the anode screen can be seen from FIGURE 4. The filling of the tube consists of neon of 85 mm. of mercury column. To prevent delays in the ignition of the guard discharge between the projection 9 and the anode screen 5, one wing of the screen 8 has provided on it a small amount of fine pulverulent titanium 10 having absorbed in it the radio-active material tritium to an amount of about $1\mu\text{C}$. A nickel pole 11 serves as an anode for atomising the peak 6 and the auxiliary anode 7 by sputtering in a glow discharge.

In FIGURE 5, the tube is indicated by 12, the cathode by 13, the anode by 14, the anode screen by 15, the cathode screen by 18, the projection of the cathode by 16 and the auxiliary anode by 17. The cathode screen 18 is connected through a resistor 19 of 10 megohms to the cathode lead and the anode screen 15 is connected through a resistor 20 likewise of 10 megohms to the anode lead. The tube is fed from an alternating-voltage source 21 of 220 volts.

60 Branched from the anode lead, through a sensitive element 22, is the connection to the igniting anode 17, which includes a resistor 23 which is also connected to the cathode through a capacitor 24. The sensitive element 22 comprises a photo-resistor of cadmium sulphide. The photo-resistor has a very high resistance if not radiated by light and a low resistance upon radiation. If light falls on the resistor 22, the voltage set up at the igniting anode 17 during the positive phase is such that the auxiliary discharge and hence the main discharge in tube 12 is ignited. The relay 25 is then energised and closes contacts 26. The tube 12 is still ignited upon control by the auxiliary anode at an alternating voltage of 175 volts from the source 21, whilst ignition still does not occur at 275 volts without control voltage at the igniting anode 17.

What is claimed is:

1. A glow discharge device comprising a glow discharge tube including an envelope containing an ionizable gaseous medium, a cold, non-activated cathode, an anode, and an igniting anode all within said envelope, said anode and cathode electrodes defining a main discharge path therebetween and said igniting anode and said cathode defining an auxiliary discharge path therebetween, a tubular screen electrode substantially surrounding said anode and interposed between the cathode and igniting anode, and a second screen electrode positioned on the side of said tubular screen electrode remote from the anode, means including a resistor connecting said second screen electrode to said cathode, means including a resistor connecting said tubular screen electrode to said anode, and means to apply a cyclic alternating potential between the cathode and anode, at least one of said screen electrodes having a projection directed towards the other screen electrode whereby with the alternating potential applied between the cathode and anode a relatively weak discharge occurs between the two screen electrodes at a distance from the main discharge path at which delays in ignition in the auxiliary discharge path are prevented without a decrease in igniting potential in the main discharge path.

2. A glow discharge device comprising a glow-discharge tube including an envelope containing an ionizable gaseous medium, a cold, non-activated cathode, an anode, and an igniting anode all within said envelope, said anode and cathode electrodes defining a main discharge path therebetween and said igniting anode and said cathode defining an auxiliary discharge path therebetween, a cylindrical screen electrode surrounding said anode and interposed between the cathode and igniting anode, and a second screen electrode positioned on the side of said cylindrical screen electrode remote from the anode and being shielded therefrom by said cylindrical screen electrode, means including a resistor connecting said second screen electrode to said cathode, means including a resistor connecting said cylindrical screen electrode to said anode, and means to apply a cyclic alternating potential between the cathode and anode, at least one of said screen electrodes having a projection directed towards the other screen electrode whereby with the alternating potential applied between the cathode and anode a relatively weak discharge occurs between the two screen electrodes at a distance from the main discharge path at which delays in ignition in the auxiliary discharge path are prevented without a decrease in igniting potential in the main discharge path.

3. A glow discharge device comprising a glow dis-

charge tube including an envelope containing an ionizable gaseous medium, a cold, non-activated cathode, an anode, and an igniting anode all within said envelope, said anode and cathode electrodes defining a main discharge path therebetween and said igniting anode and said cathode defining an auxiliary discharge path therebetween, a tubular screen electrode substantially surrounding said anode and interposed between the cathode and igniting anode, and a second screen electrode positioned on the side of said tubular screen electrode remote from the anode and spaced from the main discharge path, means including a resistor connecting said second screen electrode to said cathode, means including a resistor connecting said tubular screen electrode to said anode, and means to apply a cyclic alternating potential between the cathode and anode, at least one of said screen electrodes having a projection directed towards the other screen electrode whereby with the alternating potential applied between the cathode and anode a relatively weak discharge occurs between the two screen electrodes at a distance from the main discharge path at which delays in ignition in the auxiliary discharge path are prevented without a decrease in igniting potential in the main discharge path.

4. A glow discharge tube comprising an envelope containing an ionizable gaseous medium, a cold, non-activated cathode, an anode, and an igniting anode all within said envelope, said anode and cathode electrodes defining a main discharge path therebetween and said igniting anode and said cathode defining an auxiliary discharge path therebetween, a tubular screen electrode substantially surrounding said anode and interposed between the cathode and igniting anode, a second screen electrode positioned on the side of said tubular screen electrode remote from the anode and spaced from the main discharge path, at least one of said screen electrodes having a projection directed towards the other screen electrode whereby with the alternating potential applied between the cathode and anode a relatively weak discharge occurs between the two screen electrodes at a distance from the main discharge path at which delays in ignition in the auxiliary discharge path are prevented without a decrease in igniting potential in the main discharge path.
